UNITED STATES PATENT OFFICE.

WILLIAM DICKS, OF BEAVERFALLS, PENNSYLVANIA, ASSIGNOR OF ONE-HALF TO GEORGE H. BLAXTER, OF PITTSBURG, PENNSYLVANIA.

GUIDING DEVICE FOR TUBE-MILLS.

SPECIFICATION forming part of Letters Patent No. 693,381, dated February 18, 1902.

Application filed May 16, 1901. Serial No. 60,492. (No model.)

To all whom it may concern:

Be it known that I, WILLIAM DICKS, a citizen of the United States, residing at Beaverfalls, in the county of Beaver and State of Pennsylvania, have invented or discovered a new and useful Improvement in Guiding Devices for Tube-Mills, of which the following is a full, clear, and exact description, reference being had to the accompanying drawings, forming part of this specification, in which—

Figure 1 is a view in side elevation of a piercing-mill provided with my improvement. Fig. 2 is a horizontal sectional view indicated by the line 11 11 of Fig. 1, illustrating the commencement of the operation. Fig. 3 is a similar view at the end of the operation. Fig. 4 is a perspective view of the bushing.

My invention relates to the art of piercing blanks for seamless tubing; and it consists in a device for preventing free movement of the advancing end of the shell as it travels over and away from the piercing point or plug.

Heretofore in piercing or expanding long billets the forward end of the shell has been unrestrained, so that it was free to drop down onto the supporting-bar for the plug, and also by reason of the high rotating velocity the end was free to vibrate and whip violently around the bar, tending to distort the hollow billet and injure the bar, while preventing the manufacture of a perfect billet. My invention is designed to overcome this trouble in the manner hereinafter set forth.

Referring to the drawings, 2 3 are the disks of the mill, of different diameters, having the same peripheral speed, rotating in opposite directions, as indicated, and vertically offset above and below each other, so as to secure the forward feed of the billet due to such arrangement, in the manner well understood and practiced in this art.

4 is the piercing plug or point, located midway between the different horizontal centers and suitably located with relation to the disks to penetrate the billet as it is advanced, the plug being secured upon the end of the usual bar 5, free to rotate and positively held in position by a rigid bearing at the opposite

end (not shown) and also by a suitable guiding-frame 6, located in convenient relation to the disks.

7 is a bushing slidably mounted upon the bar 5 and adapted in its initial position to enter a bearing-opening in the guiding-frame 6, closely adjacent to the plug 4, so that the plug is positively and accurately held in alignment during the first portion of the piercing operation. The bushing is circular in form, as shown, and tapers toward the point, as at 8, being of a suitable size to partly enter the forward hollow end of the pierced billet as it advances, whereby such end of the billet will embrace it with a comparatively tight fit. As the billet continues to advance it will push the bushing ahead of it out of its bearing in the guiding-frame 6 and along the bar to the limit of travel of the billet until it is finished, as indicated in Fig. 3, and during such operation the bushing will provide a positive central bearing for the billet, holding it steady and entirely overcoming the "whipping" action referred to. At the end of the rolling operation the bar and the hollow billet are removed, the billet is disengaged, and the bar and bushing are again adjusted in position ready for another operation. In cases where an already-pierced billet is again passed over an enlarging-plug the bushing is employed in the same manner as has been described, with the same beneficial results.

The advantages of my invention will be appreciated by those skilled in the art, and in practice I have found that it entirely overcomes the objections noted and provides a simple, cheap, and efficient remedy therefor.

Having described my invention, what I claim is—

1. In combination with the supporting-bar for the plug or point of a piercing-mill; a bushing slidably mounted on the bar and provided with a tapered extension adapted to enter the hollow billet and to slide with it along the bar.

2. In combination with the supporting-bar for the plug or point of a piercing-mill; a bushing slidably mounted on the bar, adapted to support the end of the hollow billet in

alinement with the bar and to slide with it along the bar.

3. A device for the purpose described comprising a circular tapered bushing adapted to slide upon the bar supporting the plug or point, and to enter the hollow billet.

4. In combination with the disks or rolls of a piercing-mill, a plug or point and the supporting-bar therefor, a tapered bushing slid-
ingly mounted on the bar, adapted to enter the hollow billet.

5. In combination with the disks or rolls of a piercing-mill, a plug or point, a supporting-bar therefor, and a guiding-frame; a tapered bushing slidingly mounted upon the bar,

adapted to be inserted in the guiding-frame, and to enter the hollow billet.

6. In combination with the disks or rolls of an enlarging or expanding mill, a plug or ball, a supporting - bar therefor, and a guiding-
frame; a tapered bushing slidingly mounted upon the bar and adapted to be inserted in the guiding-frame, and to enter the hollow billet.

Signed at Beaverfalls, Pennsylvania, this 25
9th day of April, 1901.

WILLIAM DICKS.
